DE 5. 187

6. 20. 1848

Design,
Robert Ward of the Artisan Association, improved Patent
Invented June 20th 1848.

Dec. 1867

Robert Wood and Wm Hamilton Philadelphia County Penna
(Letters Patent N° 187 dated June 20th 1848)
(assigned to R. Wood)

The schedule referred to in the above Patent
and making part of the same.

To whom it may concern:

Be it known that we Robert Wood and W^m
Hamilton all of the County of Philad. in the State
of Pennsylvania have invented or produced a new &
useful design for a cast iron bracket for the support of
balconies. And do hereby declare that the following
is a full and exact description of the same.

Plate 1 Fig 1 represent the bracket the ledging or top
marked a is ornamented by a continued grician
leaf the lower parts are composed of a cluster
of ornaments commencing with a very rich Horn
of Plenty as marked B. with fruit & leaves inter-
spersed with light scroll work the whole being
completed by a grape vine twisting its joints &
leaves around the scroll & finally terminating by
a branch of grapes & foliage gracefully galling or hang-
ing over the end C. Fig 2 represents the upper front part
of section a with the flange at the end marked B. for
the purpose of securing it to the wall.

We have thus described the several plates and represented
the bracket which we wish to patent And do hereby
claim the exclusive right to the said ornamental de-
signs as we have arranged them and displayed them
in the bracket of the shape and configuration of the one
displayed and represented
